UNITED STATES PATENT OFFICE.

HARRY BLECKER AND SAMUEL K. KRAPP, OF READING, PENNSYLVANIA.

CAP WITH EYESHADE.

Application filed July 21, 1924. Serial No. 727,199.

To all whom it may concern:

Be it known that we, HARRY BLECKER, a citizen of Russia, and SAMUEL K. KRAPP, a citizen of the United States, both residing at Reading, in the county of Berks and State of Pennsylvania, have invented certain new and useful Improvements in Caps with Eyeshades, of which the following is a specification.

10 This invention relates to a combined cap and eye-shade, the cap being of ordinary construction and slightly modified to accommodate the improved eye-shade.

15 The primary object of the invention is to provide a combined cap and eye-shade, the latter being attached to the cap vizor and being so shaped as to extend downwardly and outwardly beneath the vizor and away from the user's face to protect 20 the user's eyes from the glare of the sun or approaching headlights or the like.

25 A further object of the invention is to provide a cap with a flexible transparent eye-shield, which may be detachably connected to the under side of the vizor when in use, or stored within the forward portion of the cap body when not in use, where it is held out of sight and at no discomfort to the user, and where it tends to stiffen and hold flat the fold of the cap above the vizor.

30 With the foregoing objects outlined and with other objects in view which will appear as the description proceeds, the invention 35 consists in the novel features hereinafter described in detail, illustrated in the accompanying drawing, and more particularly pointed out in the appended claims.

35 Referring to the drawings:

40 Fig. 1 is a front view of a cap with the improved eye-shade attached thereto.

45 Fig. 2 is a side view partly in longitudinal vertical section.

Fig. 3 is an underside or bottom plan view of a portion of the cap with the shade attached.

50 Fig. 4 is a section on the line 4—4 of Fig. 3.

55 Fig. 5 is a diagrammatic view.

In the drawing, 1 designates an ordinary cap body provided with a peak or vizor 2. For the purpose of the present invention, two snap fastener sockets 3, 3 (see Fig. 4) are attached to the vizor near the opposite ends of the latter, though obviously other

fastening means may be employed; and as this vizor is of relatively stiff material, it will be understood that the fastenings 3, 3 are spaced substantially the same distance apart at all times. The cap is also 60 modified, as shown, by arranging two spaced retaining loops 4, 4 within the body, one end of each loop member being secured to the forward fold of the cap or its lining by stitching at the points 5, 5, and 65 the other ends being secured at 5^a, 5^a between the cap edge and the sweat band 6, which latter in the construction shown extends only part way around the head opening.

70 The improved eye-shade 6^a which we combine with this cap, is formed preferably of a single piece of flexible transparent material, such as celluloid or the like, and as shown in Fig. 3, the upper edge of this 75 shade is preferably of general concave shape, with the central edge portion extending upwardly at 7 to bear upon the under side of the cap vizor. The lower edge of the shade may be of any suitable 80 shape, but we prefer to provide the central edge portion of the same with a concaved portion 8 substantially parallel to the edge portion 7, to accommodate the nose of the 85 user.

85 The shade is preferably provided at its ends, as shown, with fastening balls 9, 9, to engage sockets 3, 3, and it is pointed out that when the shade is laid out flat, the distance 90 between the fastening elements 9, 9, is about one inch greater than the distance between the fastening elements 3, 3 of the vizor, so that the entire upper edge of the shade 6^a will contact with the under side of the vizor 95 when the fastening elements 3, 3 and 9, 9 are connected together. Due to the differences in distance between the fastening elements 3, 3 and the fastening elements 9, 9, the central portion of the shade will be 100 bulged outwardly and the entire shade with the exception of its secured end portions will extend at varying angles to the under surface of the vizor. Consequently, the shade will automatically adjust itself when the wearer adjusts the cap on his head and furthermore, the upper edge of the shade will have a tendency to push upwardly on the vizor and cause the shade to extend downwardly and outwardly relatively to the underside of the vizor, in proper position 110

parting from the spirit of the invention as
expressed in the claims. 35

What we claim is:

1. In combination with a cap having a
visor provided with spaced fastening ele-
ments arranged on the underside thereof
near the ends of said visor, a detachable eye-
shield formed of approximately flat substan-
tially stiff sheet material having fastening
elements arranged near the inner edge and
ends of the shield and spaced a greater dis-
tance apart than the fastening elements of
the visor and connected to the fastening ele-
ments of the visor, so as to cause determined
outward bowing of the applied shield. 40

2. In combination with a cap having a
visor provided with spaced fastening ele-
ments arranged on the underside thereof
near the ends of said visor, a detachable eye-
shield formed of approximately flat substan-
tially stiff sheet material having end portions
provided with fastening elements spaced a
greater distance apart than the fastening
elements of the visor and connected to the
fastening elements of the visor, so as to
cause determined outward bowing of the ap-
plied shield, said shield having a curved up-
per edge adapted to conform with the con-
tacting visor when it is applied to the latter. 55

In testimony whereof we affix our signa-
tures.

HARRY BLECKER.
SAMUEL K. KRAPP.

to shield the user's eyes without bearing
against the user's face, the concave portion
8 as shown, accommodating the nose without
contact therewith. Moreover, the bearing
5 of the convexed portion 7 of the edge
against the vizor, causes the latter to main-
tain its desired arch-shape.

When the shade is not in use, it may be
readily slipped between the retaining straps
10 4, 4 and the front fold of the cap, and there
it will occupy a position immediately above
the vizor and tend to hold the front fold
portion of the cap body in the desired flat
shape; and it may remain stored there out
15 of sight and at no discomfort to the wearer,
and the cap appears as an ordinary dress
cap with the shade feature completely hid-
den from view.

At times it may be desirable, and our
20 invention provides for carrying two or more
eye shades within the retaining straps 4, 4,
so that selection may be made as to a shade
of the proper density of tint or coloring for
a special purpose or need, in withdrawing
25 one for use under the vizor.

While we have shown and described loops
4, 4 for retaining the eye shade stored within
the cap fold, it may be desirable in some
cases to employ instead properly spaced
30 socket fasteners secured to the cap or its
lining; and it is obvious that other changes
and modifications may be made from the
preferred embodiment set forth, without de-
